Attorneys

UNITED STATES PATENT OFFICE.

ABRAM LANG, OF EDEN CENTER, NEW YORK.

NON-SLIPPING HORSESHOE.

No. 884,504.

Specification of Letters Patent. Patented April 14, 1908.

*Application filed September 6, 1906, Serial No. 333,461. Renewed February 24, 1908. Serial No. 417,394.

To all whom it may concern:

Be it known that I, ABRAM LANG, a citizen of the United States, residing at Eden Center, in the county of Erie and State of New York, have invented a new and useful Improvement in Non-Slipping Horseshoes, of which the following is a specification.

This invention relates to the class of horseshoes consisting of a pad or tread-plate of rubber or similar material adapted to be secured by straps or other fastenings to the underside of an ordinary iron shoe to prevent the animal from slipping on wet or icy pavements.

One of the objects of my invention is the construction of a strong, light and durable shoe of this character.

Other objects are to improve the connections between the attaching straps and the tread-plate, and to so construct the shoe that twisting or displacement of the same on the iron shoe is effectually prevented.

In the accompanying drawings: Figure 1 is a perspective view of the improved horseshoe. Fig. 2 is a top plan view thereof, with the fastening straps and clips omitted. Fig. 3 is a transverse section in line 3—3, Fig. 2.

Similar letters of reference indicate corresponding parts throughout the several views.

A indicates the pad or tread-plate of the shoe which bears against the underside of the ordinary iron horseshoe B and which has the general contour of the same, as shown. This tread-plate is preferably molded of soft rubber, but felt or other suitable material having non-slipping properties may be substituted therefor, if desired.

C, C indicate plates of metal or other strong material firmly secured to the upper side of the tread-plate A by rivets c, or other suitable fastenings the heads of which are countersunk in the tread-plate and in the construction shown are provided with washers c' to increase their bearing surface and render them less liable to be stripped from the tread-plate. The metallic plates C follow the general configuration of the tread-plate and are preferably hinged together at their front ends by a vertical pin b, so that they are free to move toward and from each other and follow the contracting and spreading movements of the heel-portions of the tread-plate in adapting the latter to hoofs of different sizes, the elasticity of the tread-

plate permitting of this adjustment within certain limits.

E indicates a fastening strap connecting the front portions of the metallic plates C and adapted to extend across the front side 60 of the animal's hoof, the strap having a suitable buckle, as shown. F is a similar strap connecting the rear ends of said plates and adapted to extend across the back of the hoof for securing the tread-plate in place. In 65 the construction shown in the drawings, the front strap passes through loops g carried by clips h which are pivoted by transverse pins or rivets h' to lugs or ears i projecting upwardly from the outer edges of the metallic 70 plates C, these ears and clips being preferably flush, or nearly so, with the lateral edges of the tread-plate, as shown. The rear strap F passes through loops j connected by chains j' or similar flexible connections with 75 clips k which are pivoted by transverse pins k' to lugs or ears l projecting upwardly from the outer edges of the metallic plates C, near the rear ends thereof. Each of the chains is preferably inclosed by a tube m of rubber or 80 other soft material to avoid chafing the back of the hoof, one of these tubes being omitted in Fig. 1, to clearly show the chain j'.

The pivotal or swiveling connections between the fastening straps and the metallic 85 plates C above described permit the straps to adapt themselves to the shape of the hoof, so as to tightly embrace the same.

n indicate lugs or stops arranged at the inner edges of the plates C, preferably opposite 90 the rear lugs l and located at the proper distance from the latter to admit the heel portions of the iron shoe between them. By this construction said heel-portions are confined between the inner and outer lugs l, n, 95 thus reliably holding the tread-plate from twisting or lateral displacement on the iron shoe. The front lugs h also contribute toward this result.

By employing separate front and rear 100 straps, as shown, the tread-plate can be more securely fastened to the hoof than by the use of a single strap which encircles the hoof. If desired, the metallic attaching plates may be embedded or vulcanized in the body of the 105 tread-plate.

I claim as my invention:

1. A non-slipping horseshoe adapted to be applied to an ordinary horseshoe and comprising a tread-plate, metallic plates secured 110

to the upper side of the tread plate and provided on their heel-portions with rigid inner and outer stops arranged to abut against opposite sides of the heel-portions of the ordinary shoe, substantially as set forth.

2. A non-slipping horseshoe adapted to be applied to an ordinary horseshoe and comprising a tread-plate, metallic plates secured thereto along opposite sides thereof and each 10 provided at its inner edge with a stop adapted to engage the ordinary horseshoe, and fastening means connected with said metallic plates, substantially as set forth.
3. A non-slipping horseshoe, adapted to be

applied to an ordinary horseshoe and comprising a tread-plate, metallic plates secured thereto along opposite sides thereof and each provided at its outer edge with upwardly-projecting lugs or ears and at the inner edge of its heel-portion with a similar lug, and fastening straps connected with said outer lugs, substantially as set forth.

Witness my hand this 31st day of August, 1906.

ABRAM LANG.
